UNITED STATES PATENT OFFICE.

RANSOM W. DAVENPORT, OF DETROIT, MICHIGAN, ASSIGNOR TO CHICAGO PNEUMATIC TOOL COMPANY, OF NEW YORK, N. Y., A CORPORATION OF NEW JERSEY.

HEAT ENGINE.

REISSUED

Original application filed November 29, 1922, Serial No. 603,998. Divided and this application filed April 25, 1924. Serial No. 708,936.

My invention consists in improvements in heat engines and is particularly adapted to employ in certain thermodynamic operations the novel working substance described and claimed in my co-pending application filed Nov. 29, 1922, Ser. No. 603,998 of which original application the present application is a division; and for performing upon the said novel working fluid such 10 heat-transforming operations as are described and claimed in my application filed June 21, 1922, Ser. No. 570,015 also co-pending.

This present and the two aforesaid inventions constitute a closely related series of 15 inventions.

Besides the above mentioned objects, the present invention provides means for utilizing the peculiar advantages inherent in the aforesaid inventions, and applying them to the practical cooling of refrigerators. Other objects of my invention will appear hereinafter.

All refrigerating apparatus of the compression type hitherto known or used falls 25 into one of two perfectly distinct and separate classes, i. e., the vapor-compression class or compressor-condenser-expander type, and the cold air type or compressor-cooler-expansion motor class. This separation is but the natural result of the essential 30 and basic differences between the liquid-vapor refrigerants used in the former, and the ideal gas refrigerants used in the latter class of apparatus. It is emphasized that in 35 the vapor compression type of heat engine the refrigerating effect is obtained not by expansion but by vaporization of liquid at constant temperature and pressure, which 40 liquid is fed as liquid, and without expansion, through a throttle valve loosely called the "expansion valve", whereas in the cold-air machine the entire refrigerating effect 45 is obtained by expanding air or other gas (not vapor) in an expansion motor.

My improved heat engine differs from both the above described types of heat engine in that I employ both an expansion device and a boiler or vaporizing element in 50 novel combination with a compressor and a condenser, and in other respects herein-after set forth, and is depicted in certain representative forms in the accompanying drawings.

Fig. 1 is a front elevation-section of a 55 form of my invention including the refrigerator.

Fig. 2 is a side view of parts of same.

In the form shown in Figs. 1 and 2, in which figures like parts have like numerals, 60 my invention may be described as follows: 1 is an electric motor geared to a compressor 2 which discharges into condenser 3. The evaporator comprises the headers 4 and 5 connected by the ribbon-shaped duct 6, with 65 the separator 7 forming the outlet and nozzle 8 the inlet. The outlet 7 is connected to the intake of the pump 2 by the pipe 9, and the inlet nozzle 8 is connected to the condenser 3 by the pipe 10 which is placed 70 inside the pipe 9 to form a heat exchanger therewith.

The insulated refrigerator cabinet 11 contains compartments 12 and 13 each of which may also be insulated, and the evaporator 75 traverses all three as shown. Shelves 14 to 17 may be used to carry the articles to be cooled.

This embodiment of my invention operates substantially as follows: after charging the system with a proper quantity of a suitable working substance of the type before mentioned, with a supply of the liquid component in the evaporator as shown, and air and vapor in the rest of the space, the 80 motor 1 is started and the compressor 2 compels the circulation of the working substance. The total pressure in the evaporator 4-5-6 falls while the total pressure in the condenser 3 rises, thus causing the liquid in 85 the evaporator to evaporate and absorb heat from the refrigerator, and the vapor in the condenser to liquefy and eject heat to any suitable cooling medium as air or water (not shown). The expander 8 offers suitable resistance to the flow of gas vapor and liquid fed to it in contiguous streams through duct 10 from the condenser, thus maintaining suitable difference in pressure 90 between condenser and evaporator. The 95 liquid in the evaporator is caused to emulsify with the gas and vapor by the action of the expander 8, and this I find to be of great advantage in "facilitating evaporation and rapid cooling" of liquids of relatively 100 low vapor tension, such as alcohol etc., which, in the old vapor compression types 105 of heat engine, lacking my combination of

expander and evaporator, lie inert and unable to produce practical refrigerating effect. It is to be understood that the indicated gauge suction or back pressure is higher than that corresponding with the temperature of the liquid refrigerant, which temperature is limited only by the partial vapor pressure effective at a given time and place.

10 By the combination with the expander, of my improved emulseur-evaporator, I am enabled to derive the further advantage of operating at a plurality of refrigerating temperatures, since I find that the lower header 15 4 tends to be colder than the upper header 5, when circulation between them is restricted by any suitable means, such as the flattened or ribbon-shaped duct 6. I may apply this peculiar advantage in any desired way 20 as, for example, by combining my improved evaporator with suitably insulated chambers 12 and 13 so disposed that the lower one 12 is colder than the others, while chamber 13 a little higher up and nearer header 5 will 25 be warmer and the main chamber or cabinet itself may be still milder in temperature. By this arrangement water may be frozen in ice-chamber 12, raw meats, milk, butter etc. may be kept at temperatures around that of 30 melting ice in chamber 13, while the main compartments formed by the shelves 15, 16, 17 may be kept at, for instance, 50 degrees F. for general articles such as cooked foods and raw vegetables. Since the bulk of the 35 heat transfer occurs at this relatively high temperature, I am enabled to procure much higher economy than was possible where the refrigerant must be evaporated at a temperature and pressure low enough to make ice, 40 while the cabinet itself was operated at a lower temperature than is really needed, as was necessarily the case with all former refrigerators, cooled by mechanical means.

Besides the obvious advantages of my invention, other advantages inhere such as the 45 fact that with the aid of my improved refrigerant before mentioned, my apparatus may be made self-regulating. For example, using carbon tetrachloride as the liquid component of my working substance, the freezing point of which is around zero F., the nozzle 8 freezes up at this temperature thus limiting the temperature in all compartments of the refrigerator and simultaneously unloading the compressor so that the power required is practically as low as that with blanked intake. The costly and troublesome 50 thermostat always a vital part of the former automatic refrigerating machines is, by virtue of the cooperation of my improved refrigerant with the present invention, done away with.

Likewise the trouble-making expansion 55 valve which, in the old systems, was always required in order to maintain the liquid seal

essential between the condenser and expander, is, by my invention, dispensed with along with the seal.

The reversibility of the heat engine above described may be extraordinarily high owing to the temperature gradient in the refrigerator.

I claim:

1. Refrigerating apparatus utilizing as a refrigerant a physical mixture of a liquid 75 and a gas inert to and insoluble in said liquid comprising a compressor, means to operate said compressor, a refrigerating element for containing the liquid refrigerant, a continuously open nozzle opening into said element, 80 a condenser, ducts connecting said compressor to said element and to said condenser respectively, and a duct through which contiguous streams of liquid and gas pass from said condenser to said nozzle. 85

2. Refrigerating apparatus of the closed cycle type comprising a plurality of refrigerating chambers, vessels containing an evaporable liquid disposed in thermal relation with said chambers, ducts arranged to connect said vessels to form a series, means including a nozzle for expanding into the first vessel of said series a stream of mixed gas and vapor, means for removing gas and vapor from the last vessel of the series to 95 provide the stream forced into said first vessel, and means in said cycle for maintaining the aforesaid liquid in said vessels. 99

3. In a heat engine of the compressor-condenser-evaporator type utilizing as a working substance a liquid and a gas substantially inert and insoluble in the liquid, a compressor, a condenser, and an evaporator, said evaporator for containing a body of said liquid, a De Laval nozzle arranged to discharge into said evaporator, and a pipe connecting said nozzle with said condenser, said nozzle area being so proportioned as to pass contiguously both the liquid and the gaseous components of the refrigerant. 100

4. In refrigerating apparatus for utilizing a refrigerant having liquid and gaseous components, an evaporator for containing the liquid component of the refrigerant, means continuously to force the gaseous component of the refrigerant in a closed cycle through the liquid component in said evaporator, and means for withdrawing heat from said gaseous component at one point in said cycle. 105

5. Refrigerating apparatus for utilizing a refrigerant having liquid and gaseous components comprising an evaporator for containing the liquid component of the refrigerant, means continuously to withdraw the gaseous component and the vapor of the refrigerant from the evaporator, cool said mixture and liquefy the refrigerant and return said mixed liquid and gas to the bottom of the evaporator. 125

6. Refrigerating apparatus for utilizing a refrigerant having liquid and gaseous components comprising a heat absorbing element for containing the liquid component of the refrigerant, a pump withdrawing the gaseous component of the refrigerant from the top of said element, a heat ejecting device through which said gaseous component is forced by said pump, and a duct leading from said device to the base of said element and providing a restricted opening so proportioned as to pass the mingled condensed and non-condensable components of the circulated refrigerant which expand directly into and up through the liquid in said element.
7. Refrigerating apparatus for utilizing a refrigerant having liquid and gaseous components comprising a heat absorbing element for containing the liquid component of the refrigerant, a pump withdrawing the gaseous component of the refrigerant from the top of said element, a heat ejecting device through which said gaseous component is forced by said pump, and a duct leading from said device to the base of said element and terminating in a De Laval nozzle, the nozzle area being so proportioned as to pass continuously and in contiguity both the condensed and the non-condensable products of said heat ejecting device.
8. Refrigerating apparatus for utilizing a refrigerant having liquid and gaseous components comprising a heat absorbing element for containing the liquid component of the refrigerant, a pump withdrawing the gaseous component of the refrigerant from the top of said element, a heat ejecting device through which said gaseous component is forced by said pump, a duct leading from said device to the base of said element and providing a restricted opening of such size as to pass the mingled condensed and non-condensable components of the circulated refrigerant directly into the liquid in said element, and means for precooling the circulated refrigerant intermediate said device and said element.
9. Refrigerating apparatus for utilizing a refrigerant having liquid and gaseous components comprising a heat absorbing element for containing the liquid component of the refrigerant, a pump withdrawing the gaseous component of the refrigerant from the top of said element, a heat ejecting device through which said gaseous component is forced by said pump, and a duct leading from said device to the base of said element and providing a restricted opening of such size as to pass the mingled condensed and non-condensable components of the circulated refrigerant directly into the liquid in said element, said duct being brought into thermal contact with the relatively colder gaseous component being withdrawn from the top of said element by said pump thereby to precool the circulated refrigerant.
10. Refrigerating apparatus for utilizing a refrigerant having liquid and gaseous components comprising a heat absorbing element for containing the liquid component of the refrigerant, a pump withdrawing the gaseous component of the refrigerant from the top of said element, a heat ejecting device through which said gaseous component is forced by said pump, and a duct leading from said device to the base of said element and providing a restricted opening of such size as to pass the mingled condensed and non-condensable components of the circulated refrigerant directly into the liquid in said element, a portion of said duct being disposed within the top of said element thereby to precool the circulated refrigerant.
11. In refrigerating apparatus for utilizing as a refrigerant a physical mixture of a liquid and a gas substantially inert to and insoluble in said liquid, a refrigerating element for containing the liquid portion of the refrigerant, and means producing a rapid ebullition of said liquid comprising members forming a closed cycle through which the gaseous portion of the refrigerant is circulated and including a continuously open port in said element through which said gaseous component is forced to bubble up through said liquid component.
12. In refrigerating apparatus for utilizing as a refrigerant a physical mixture of a liquid and a gas substantially inert to and insoluble in said liquid, a refrigerating element for containing a body of the liquid, means producing a rapid ebullition of said liquid body including a compressor arranged to withdraw the gas and the vapor of the liquid from said element and return the same under pressure to said element adjacent the bottom thereof, and means for removing heat from said gas-vapor stream before it is returned to said element.
13. In refrigerating apparatus for utilizing as a refrigerant, a physical mixture of a liquid and a gas substantially inert to and insoluble in said liquid, a refrigerating element for containing a body of the liquid, a compressor arranged to withdraw the gas and the vapor of the liquid from said element, means for removing heat from said gas-vapor stream, and means for returning said gas-vapor stream under pressure to said element comprising a continuously open port in said element.
14. In refrigerating apparatus for utilizing as a refrigerant, a physical mixture of a liquid and a gas substantially inert to and insoluble in said liquid, a refrigerating element for containing a body of the liquid, a compressor arranged to withdraw the gas and the vapor of the liquid from said ele-

- ment, means for condensing at least a part from said compartment at different temperatures.
15. A refrigerator having insulated walls and an elongate refrigerating element vertically disposed therein, and means causing said element to absorb heat from said refrigerator at different temperatures at vertically spaced points thereof.
16. A refrigerator having insulated walls and an elongate refrigerating element vertically disposed therein, and means causing said element to absorb heat from said refrigerator at upwardly spaced points on said element at progressively higher temperatures.
17. A refrigerator having at least three separate heat insulated compartments and a single heat absorbing element in thermal contact with the interior of all said compartments, said compartments and said element being so arranged that heat is removed
18. A refrigerator having heat insulated walls and a heat absorbing element therein vertically disposed and extending substantially from the bottom to the top of the space to be cooled and a series of separately insulated compartments within said space partly enclosing said element and maintained by the latter at progressively higher temperature.
19. A refrigerator having heat insulated walls providing an interior space to be cooled, a compartment in the bottom of said space to be maintained at a temperature below freezing, a compartment above said first named compartment to be maintained at a temperature slightly above freezing, the remainder of the space being arranged to be maintained at a somewhat higher temperature and a single heat absorbing unit having parts in thermal contact with the interior of each of said compartments.

RANSOM W. DAVENPORT.
